CARBURETER.

1,089,471

Specification of Letters Patent. Patented Mar. 10, 1914.

Application filed February 14, 1913. Serial No. 748,624.

To all whom it may concern:

Be it known that we, HOWARD H. HUNT and WILLIAM S. PELLOUBET, citizens of the United States, and residents of Los Angeles, 5 in the county of Los Angeles and State of California, have invented certain new and useful Improvements in Carbureters, of which the following is a specification.

Our invention pertains to carbureters, and 10 it has special reference to mechanism for producing a carbureted gas suitable for lighting or heating purposes.

Our objects are to provide a machine for this purpose which is not only simple in 15 construction but also very compact in its structural arrangement, and which provides positive means for supplying air and hydro-carbon oil in the proper proportion, and which will operate automatically and accurately with the smallest amount of power, 20 as will now be set forth in detail.

In the accompanying drawings, Figure 1 is a front view of our improved carbureter. Fig. 2 is an end view. Fig. 3 is a 25 vertical cross section on line A—A of Fig. 2. Fig. 4 is a vertical longitudinal section on line B—B of Fig. 1, showing some of the parts in full and others in section. Fig. 5 is a vertical cross section on line C—C of Fig. 30 2. Fig. 6 is a vertical longitudinal section on line D—D of Fig. 1. Fig. 7 is a vertical section through a portion of the air compression cylinder. Fig. 8 is a side view of one of the air compartments of the air compression cylinder, partly in section. Fig. 9 35 is a side view, enlarged, of the gasometer, partly in section, to show the imperforate partitions therein, and Fig. 10 is an enlarged side view of the gasolene tank, showing the 40 filling point and outlet valve.

In carrying out our invention, we construct a rectangular body 12, of suitable sheet metal, which is preferably mounted on legs 13, and provided with a top 14, suitably packed, as at 14', and held by screws (Fig. 10). This top has an opening at one end with a threaded closure cap or plug 15, by means of which oil may be supplied to the tank within. Longitudinally through 45 this body, at one side of the central line, is a horizontally disposed tubular shaft 16 which passes out at the front end of the case, and is also depressed to receive on its projecting end a loose revoluble drum 17. This drum

has within it a spring 18, the inner end of 5 the spring being attached to the shaft 16, as at 18', and its outer end is attached to the drum, as at 17'. A crank 19 is provided to turn the drum, and a pawl 20, hinged to a bracket on the case, is adapted to engage 20 with a series of teeth 21 on the drum, so that the drum may be held in a fixed position when the spring is wound up.

The inner end of the tubular shaft 16 is journaled within a bearing 22 (Fig. 7), 65 which bearing is attached to a vertical pipe 23 that is secured to the end of the case, the lower end of this vertical pipe being open, and terminating at a point near the bottom of the case or shell. This tubular 70 shaft 16 has a plurality of perforations 24, and it carries thereon the air compressing cylinder. Said tubular shaft 16 has a solid portion 16' to compel the air entering perforations 24 to pass into the pipe 23. The 75 cylinder 31 is, in this instance, made up of a plurality of different shells or compartments, each compartment being segmental in form, as shown at 25, Fig. 8, in which one end of the ring segment is open, as at 26, 80 and the other end closed, as at 27. In the outer wall of each segment, near the end wall 27, is an opening 28 through which the air and water enter as the segment revolves in the direction of the arrow thereon (see Figs. 85 5 and 8) and the air is discharged through the open end 26 by the pressure of the water. These segments are held in position by means of end and intermediate disks 29, 30, 90 respectively, and an outer cylindrical shell 90 31 which also covers the gaps between the open and closed ends of the segments. When these segments are placed in position, the openings 28 are staggered so that they are not in line with each other. Each opening 28 at the closed end of each segment coincides with a hole 28' through the outer shell 31, as shown in Fig. 7, and, therefore, the discharge of air from the open ends 26 follow each other as the cylinder turns. 100

Alongside the air compressing drum is mounted the carbureter proper. This comprises a rectangularly formed shell 32, open at its lower side, and fixed by horizontal pivots to one of the side walls, as at 33 (Fig. 105 5), and to a bracket 34, the pivotal point 33' being approximately one quarter of the length of the shell back from the front end,

so that the rear end of this carbureter shell has a limited vertical movement, as shown, for instance, by the dotted line 35, Fig. 6. The top of the shell 32 has a longitudinally disposed bar 36 which extends across the pivotal point. This bar carries an adjustable sliding weight 37, so that the oscillating carbureter shell may be properly balanced, for purposes which will be herein-
10 after explained.

Interiorly, the carbureter shell has near its forward end, substantially on a line with the pivot 23, a vertical partition wall 38 which extends down approximately half
15 way to the lower end of the shell. Parallel with this partition, spaced apart suitable distances, are downwardly projecting screens 39 of suitable foraminous material, such as burlap, canvas or other fabric that is capable
20 of absorbing and carrying up the hydrocarbon oils within the shell.

At the front end of the shell, between the partition 38 and the end of the shell, is the air inlet pipe 40, the open upper end of
25 which is near the top of the shell. This air pipe leads from the vertical pipe 23 which connects with the perforated tubular shaft 16 of the air compressing cylinder. Within the rear or opposite end of the shell, is a vertical gas discharge pipe 41, the upper end of
30 which is close to the top of the shell, while its lower end has a right-angled horizontal extension 42 which passes out at the rear end of the containing shell, and from which the
35 gas is distributed. The horizontal pipe 44 is closed at its outer end, and receives the oil supply through its upright branch pipe 45, the oil being conducted to upright pipe 43 through which it is led to shell 32.
40 Alongside this pipe 41 is another vertical pipe 43, also having its upper open end near the top of the shell 32, the lower end being connected with a horizontal branch 44 which connects with a vertical pipe 45 that extends
45 up and terminates in a funnel 45', directly below the discharge valve of the oil tank 46. It will be observed in Fig. 3 that a stub pipe 47 passes through the side wall of the case above the funnel, and the outer end of this
50 pipe has a right angled bend 48 with a plug therein, this pipe being assigned for priming purposes to provide a means for supplying a small amount of oil to the carbureting shell at starting.

55 The oil tank 46 (Fig. 10), has preferably through the plug 15 a wire rod 49 with a cork 50 on its lower end. Since this rod moves freely through the hole in the plug, and as the cork floats on the oil, the height
60 of the oil in the tank can be readily observed by the looped upper end of the wire. Centrally the base of the tank 46 has a discharge opening 51, this opening being preferably formed through a plug 52 which is
65 attached by threads to a boss 53 secured to

the tank bottom. A stem 54 projects up through the discharge opening, and this stem carries on its upper end a valve 55 that closes the discharge opening when seated in the plug. The lower end of this stem 54 is hinged to a horizontal lever 56 which is pivoted to a downwardly projecting bracket 57^a at a point close to the stem 54, and the opposite end of the lever projects forwardly and rests alongside the air compressing cylinder. The long end of the lever 56, therefore, serves to hold by its weight the valve 55 firmly on its seat, and thus will normally prevent an outflow of oil from the tank 46.
70

In order to raise the lever 56, and thus cause a discharge of oil, the air compressor shaft 16 is provided with a loosely swinging lever 57, this lever being so mounted on the shaft that passes through it, that the long end 57' of the lever extends down slightly below the perimeter of the cylinder, so that when the cylinder revolves, a finger 58 on the end thereof, and projecting therefrom, will engage with the long end 57' of the lever, and thus carry it around. The short end 59 of the lever has a right angled finger 60 which is within range of the valve operating lever 56, as shown in Fig. 4, so that, as the cylinder revolves and the swinging lever is carried around, the finger 60 will momentarily raise the lever 56 and permit a small discharge of oil, thereafter again releasing the swinging lever 57 and allowing it to temporarily swing to a vertical position, as shown, for instance, in Fig. 3 since the long end 57' of the lever is heavier than the short end 59. The oil thus discharged passes from the funnel 45' down through the pipe 45 and up through the pipe 43, where it is discharged into the carbureter shell 32.
85

In order to be able to regulate the turning movement of the air compressor, a braking device is provided, which is shown in Figs. 3, 4 and 5. Around the compressing cylinder, at any suitable point, is mounted a brake band 62, one end of this band being joined to an arm 63, which is hinged to the side wall of the case. The point of junction of the band and the arm is on top of the cylinder. The outer end of arm 63 is pivoted (see Fig. 3) to a bracket 63^b by means of a pin 63^c. The end of this arm 63 to which the band 62 is fixed, is hinged to a lever 64 which extends over to a point directly above the rear end of the oscillating carbureter shell 32, and a vertical link 65, with its lower end hinged to the top of the carbureter shell, as at 66, has its upper end hinged to the horizontal lever 64, so that the oscillation of the carbureter shell will thereby be imparted to the lever 64. Both ends of lever 64 are free to move vertically except as restrained by band 62 and rod 65, but during the time that band 62 is relaxed the
95

weight of levers 63 and 64 upon the cylinder 31 does not create sufficient friction to interfere with the rotation of said cylinder by the spring 18. The raising of rod 65 tends to depress the joint between levers 63 and 64 upon cylinder 31, thereby augmenting the braking action when the brake band 62 is tightened. The opposite end of the band 62 is attached to the lever 64, midway between its ends, so that the raising of the lever by the carburetor shell will cause the band brake to tighten and thus arrest the revolute motion of the air cylinder.

In Fig. 4 a thin reinforcement or friction band 57^b is shown extending around the cylinder 57 to receive the wear from the brake band 62 (see Fig. 3). This band 57^b is too thin to be readily shown in side elevation and is, therefore, not shown in Fig. 3 where the attempt to illustrate it might confuse it with the brake band 62.

In order that air may be freely admitted to the case 12, a vertical pipe P, open at both ends, has its lower end secured through the base of the case, and its upper end terminates near the top of the case.

The operation of the mechanism is as follows: The case is first filled with water up to the water line W, Figs. 5, 6 and 9, so that the carburetor shell is submerged about two-thirds, and the lower third of the air compressing cylinder is covered, the water being admitted at the opening 68, Fig. 1, which has a closure lid 69 (Fig. 1). The oil tank 46 may be supplied by a reservoir located apart from the apparatus. The spring 18 having been wound up, a small amount of oil is supplied to the carburetor shell 32 through the pipe 47 for starting purposes. As the air cylinder revolves in the direction of the arrow 28', Figs. 5 and 8, a definite quantity of water rushes into each segment of the cylinder through the opening 28, and when the opening 28 emerges from the water, air enters and fills the segment, so that when the opening 28 again reaches the water line and is submerged, the air thus trapped is forced out through the open end 26 of the segment so that it is trapped in the space within the segments, thence passing through the perforations 24 of the tubular shaft 16 to the pipe 23 which conveys air along pipe 40 to the interior of the carburetor shell 32. The air thus enters the shell 32 into the compartment 70 formed between the partition wall 38 and the end of the shell, so that it is compelled to pass below the lower margin of the partition 38, and, in doing so, it percolates through the film 69 of oil which rests on top of the water, this layer of oil being designated by 71, Fig. 9. As the air rises behind the partition 38, it is free to move along to the rear end of the shell toward the discharge pipe 41, and, in doing so, it must pass through the fabric

screens 39. As these screens have become moistened by the absorption of oil, the air, in passing through them, is charged with the vapor. Carburation consequently takes place in a most efficient manner during this movement of the air under these conditions. It is obvious that, if the discharge from the pipe 41 is arrested, or partially so, the pressure within the shell 32 causes its rear end to rise, and, in doing so, the brake lever 64 is raised, causing the band 62 to bind tightly against the cylinder and arrest its turning movement, until a sufficient quantity of carbureted air is withdrawn from the carbureting shell. At each revolution of the cylinder, a modicum of oil is discharged through the action of the swinging lever 57, 59, acting on the valve lever 56, so that the supply is constant, and, as the cylinder is provided with a plurality of segments so arranged that the segments discharge the air into the carbureting shell in succession, there is a constant flow of air through the carburetor.

It is important to note that by this system only a comparatively small amount of oil is supplied to the apparatus, which amount when once suitably regulated will be constantly taken up, in order to charge the air, so that the mechanism can not possibly carry only the light vapors, and leave a residue of the heavier part of the oil.

The entire mechanism is so constructed and arranged that there is no friction due to the operation of the working parts, which will in any measure tend to decrease its efficiency when running at its maximum capacity, and the adjustable weight enables us to so regulate the pressure that it is equally well adapted to supply the minimum as well as the maximum quantity of carbureted air, without impairing its quality.

What we claim as new, is:

1. In a carburetor, an oscillating shell, open at its lower end, a plurality of separated, vertical, transverse webs therein of absorbent material, a partition at one end of said train of webs and separated therefrom, the lower ends of said webs and partition being submerged in a volatile oil, means for supplying air under pressure to the compartments formed by the partition, and for forcing the air under the partition through said absorbent webs, and means connected with the oscillating shell for controlling the air supply to the shell.

2. In a carburetor, a case, an air compressing cylinder mounted within said case longitudinally at one side of the central line, a shaft on which said cylinder is mounted, means connected with its shaft to revolve said cylinder, a carbureting shell within the case alongside the cylinder, said shell having therein webs of absorbent material, means to force air through said webs from one end of the shell to the other, said cylinder

4
der and shell being partially submerged in water, and means for supplying a film of volatile oil to the water within the shell.

3. In a carbureter, a case, an air compressing cylinder mounted within said case at one side thereof, a shaft on which said cylinder is mounted to rotatably support the same, means to automatically rotate said cylinder, a carbureting shell within said case 10 to cooperate with said cylinder, said shell having therein webs of absorbent material, the rotation of said cylinder causing air to be forced through said webs from one end of the shell to the other, and liquid confined 15 in said casing and partially submerging said cylinder and shell, the liquid within the carbureting shell containing a combustible volatile element.
4. In a carbureter, a casing, means to 20 maintain within said casing a body of liquid, an air pump comprising a rotary cylinder partially submerged in said liquid, a motor tending to rotate said cylinder, a carbureter proper comprising a floating shell and carbureting screens within said shell, means to 25 conduct the air supplied by said pump to and through said screens and thence to a place of use, a brake applied to said cylinder to intermittently check the rotation thereof, and means controlled by the rise 30

and fall of the floating carbureting shell to apply and release said brake, the liquid within said carbureting shell containing a volatile combustible element.

5. In a carbureter, a casing, means to 35 maintain within said casing a body of liquid, an air pump comprising a rotary cylinder partially submerged in said liquid, a motor tending to rotate said cylinder, a carbureter proper comprising a floating shell and carbureting screens within said shell, means to 40 conduct the air supplied by said pump to and through said screens and thence to a place of use, a brake band extending around the cylinder of said pump to intermittently 45 check the rotation thereof, and a lever operated by the rise and fall of the floating shell of the carbureter proper to apply and release said brake band, the liquid within said shell containing a volatile combustible 50 element.

Signed at the city of Los Angeles, county of Los Angeles, State of California, this 24th day of December, 1912.
